Patented Nov. 9, 1965

202,771

PETROLEUM PRODUCT SERVICE STATION FOR MOTOR VEHICLES

Albert L. Wokas, 22245 Thorofare Road,
Grosse Ile, Mich.

Filed Dec. 10, 1963, Ser. No. 77,733

Term of patent 14 years

(Cl. D13—1)

FIG. 2

FIG. 3

FIGURE 1 is a perspective view of a petroleum product service station for motor vehicles showing my new design.

FIGURE 2 is a front elevation of the service station shown in FIGURE 1.

FIGURE 3 is a cross section view of the service station for motor vehicles shown in FIGURE 1 taken along the line 3—3.

I claim:

The ornamental design for a petroleum product service station for motor vehicles, substantially as shown and described.
